US00D630859S

(12) **United States Design Patent**
Koenig

(10) **Patent No.:** **US D630,859 S**
(45) **Date of Patent:** **** Jan. 18, 2011**

(54) **SHEET MATERIAL WITH PATTERN**

(75) Inventor: **John William Koenig**, Cincinnati, OH
(US)

D407,225 S 3/1999 Dwiggins et al.
D423,232 S 4/2000 Reid
D426,709 S 6/2000 Latchoo
D428,931 S 8/2000 Zulch

(73) Assignee: **The Procter & Gamble Company**,
Cincinnati, OH (US)

(Continued)

(**) Term: **14 Years**

FOREIGN PATENT DOCUMENTS

(21) Appl. No.: **29/369,310**

DE 049807176.0001 2/1999

(22) Filed: **Sep. 7, 2010**
